UNITED STATES PATENT OFFICE.

ELIJAH POWERS, OF BOONVILLE, INDIANA.

SOIL-PULVERIZER.

1,262,253.

Specification of Letters Patent.

Patented Apr. 9, 1918.

Application filed April 28, 1917. Serial No. 165,239.

To all whom it may concern:

Be it known that I, ELIJAH POWERS, a citizen of the United States, residing at Boonville in the county of Warrick and

5 State of Indiana, have invented certain new and useful Improvements in Soil-Pulverizers, of which the following is a specification.

This invention relates to an improved earth pulverizer and the principal object of 10 the invention is to provide a machine of the type described which can be drawn across a field and which will pick up lumps of earth and carry the same to rollers between which the lumps will pass and be ground 15 into fine particles, one of the grinding rollers forming a support for the rear end portion of the machine and further constituting a driving element.

Another object of the invention is to provide an improved type of conveyer for use 20 in connection with this machine, the conveyer being pivotally mounted at its upper end and adjustably supported at its lower end and including longitudinally extending 25 rods having their lower end portions extended to provide gathering fingers for lifting the lumps from the ground.

This invention is illustrated in the accompanying drawings, wherein:— 30 Figure 1 is a view showing the machine in side elevation.

Fig. 2 is a vertical sectional view taken along the line 2—2 of Fig. 1.

Fig. 3 is a vertical sectional view taken 35 along the line 3—3 of Fig. 1.

Fig. 4 is a perspective view of one of the rods forming part of the conveyer.

The improved pulverizing machine is provided with a frame or carriage 10 provided 40 with a forward truck 11 which truck carries the forward axle 12 upon which the front wheels 13 are mounted. The rear end portion of this frame is supported by the roller 14 which roller is positioned within the 45 frame and is provided with an axle 15 extending beyond one side of the frame and carries a sprocket wheel 16 for a purpose to be hereinafter described. Standards 17 are mounted upon the side bars of the frame 50 10 and serve not only to support the auxiliary roller 18 which cooperates with the roller 14 in pulverizing the lumps of earth but also serves to support the shaft 19 which shaft is positioned adjacent the upper ends 55 of the standards and carries a sprocket wheel 20 about which passes a sprocket

chain 21. It will thus be seen that when the roller 14 rotates, the sprocket chain which passes about the sprocket wheels 16 and 20 will serve to rotate the shaft 19.

A conveyer frame is carried by this machine and is provided with side bars 22, the upper ends of which are mounted upon a shaft 23 which shaft 23 is mounted by means of links 24 and carries a gear 25 meshing 60 with the gear 26 of shaft 19. Therefore as the machine is drawn across the field, rotary movement will be transmitted to the shaft 23 which shaft may be termed the driving shaft of the conveyer. The lower ends of the side 65 bars 22 are mounted upon a shaft 27 termed the driven shaft of the conveyer and journaled in the bearings 28 of the bearing yoke 29 which yoke has its bearings slidably mounted in the guide-ways 30 and is engaged intermediate its length by the stem 70 or adjusting screw 31. This adjusting or supporting screw 31 is passed through the bearing sleeve 32 carried by a cross bar 33 and is provided with a hand wheel 34 by 75 means of which it may be rotated and the yoke thus vertically adjusted and supported in the adjusted position. As this yoke is moved vertically to the proper position, the link 24 will move upon shaft 19 to permit 80 the conveyer frame to have the proper movement for vertical adjustment of the lower end thereof.

Rods 35 which provide slats constituting a screen bottom for the conveyer frame extend longitudinally between the side bars 22 thereof and are provided with upper and lower bearings or arms 36 and 37, the upper arms 36 being mounted upon shaft 19 and the lower bearing arms upon shaft 27. 90 Sprocket wheels 38 are mounted upon the shafts 23 and 27 and carry sprocket chains 39 which chains carry teeth 40. These sprocket chains when taken together, go to produce the endless conveyer having teeth for 95 engaging the lumps of earth which are lifted from the ground by the forward end portions 41 of the rods 45. The forward end portions of these rods extend beyond the conveyer frame and when taken together 100 form a scoop or rake engaging the lumps of dirt and lifting them from the ground to a position where they can be engaged by the fingers 40 and carried upwardly. When the lumps reach the upper end of the conveyer frame, they pass over the upper end 110 thereof and drop upon the auxiliary roller

18. These lumps will then pass between the rollers 14 and 18 and will be ground into fine particles. This ground earth will drop upon the ground in front of the roller 14 and the roller will pass over it. In connection with planting certain grain, it is customary to roll the field and it will thus be seen that this machine may be used for this purpose as well as for breaking up lumps of earth.

What is claimed is:—

1. An earth pulverizing machine comprising a frame, rotary supporting means for the frame, standards carried by the frame, a shaft carried by the standards, a frame, a shaft carried by the standards, a conveyer frame having upper and lower shafts, links connecting the upper shaft of the conveyer frame with the shaft of said standards, means for transmitting rotary movement from the supporting means to the shaft of said standards, means for transmitting rotary movement from the shaft of the standards to the upper shaft of the conveyer, endless conveying means passing about the shafts of the conveyer frame, and means engaging the lower end portion of the

conveyer for adjustably holding the same in a vertically adjusted position.

2. An earth pulverizing machine comprising a frame, a conveyer for carrying lumps of earth, said conveyer comprising a frame having side bars, an upper shaft carried by the side bars, links pivotally mounted and engaging the upper shaft, a lower shaft carried by the side bars, a supporting yoke having bearings rotatably mounting the lower shaft, guides carried by the frame and engaging the bearings to slidably mount the same, adjustably mounted means engaging the yoke for adjustably supporting the yoke in a vertically adjusted position, endless conveying means passing about the upper and lower shafts of the conveyer, and means for transmitting movement to the upper shaft.

In testimony whereof I affix my signature in presence of two witnesses.

ELIJAH POWERS.
